Robert H. Green, Rocky River, and George A.
Green, Lakewood, Ohio

Application July 23, 1952, Serial No. 30,714

Term of patent 14 years

(Cl. D4—3)

To all whom it may concern:

Be it known that we, Robert H. Green and George A. Green, citizens of the United States, residing at Rocky River and Lakewood, respectively, in the county of Cuyahoga and State of Ohio, have invented a new, original, and ornamental Design for a Dispenser for Toothpaste or the like, of which the following is a specification, reference being had to the accompanying drawing, forming a part thereof.

We claim:

The ornamental design for a dispenser for toothpaste or the like, substantially as shown.
